UNITED STATES PATENT OFFICE.

FAUSTINO VISINTAINER, OF LAFERTY, OHIO.

COMPOUND TOOL.

Application filed February 29, 1928. Serial No. 257,998.

This invention provides a composite tool which is readily adapted for a variety of uses generally requiring the provision of a number of individual tools, thereby economizing 5 space, cost and time, since the several tools are ready at hand for immediate use when required.

While the drawings illustrate a preferred embodiment of the invention it is to be understood that in adapting the means to meet specific needs and requirements the design may be varied and such other changes in the minor details of construction may be resorted to within the scope of the invention 15 as claimed, without departing from the spirit thereof.

For a full understanding of the invention and the merits thereof, reference is to be had to the following description and the drawings hereto attached in which,—

Figure 1 is a side view of a compound tool embodying the invention, the compass and the saw being extended.

Figure 2 is a view similar to Figure 1 showing the compass and saw in withdrawn or folded position and the tool adapted for storing.

Figure 3 is an enlarged sectional view on the line 3—3 of Figure 2.

Figure 4 is an enlarged detail sectional view on the line 4—4 of Figure 1.

Figure 5 is an enlarged sectional view on the line 5—5 of Figure 1.

Figure 6 is a detail sectional view on the line 6—6 of Figure 2, showing the parts on a larger scale.

Figure 7 is an enlarged detail view of a portion of the tool, as seen from the back.

Figure 8 is a detail sectional view of the 40 longitudinal portion of the frame showing a modification admitting of the saw blade entering edgewise into the groove.

Corresponding and like parts are referred to in the following description and designated in the several views of the drawings 45 by like reference characters.

The tool includes a frame which is substantially of U-form and comprises a longitudinal member 10 and end members 11. 50 The back of the frame is grooved, as indicated at 12 to receive and house a saw blade 13. The groove 12 may be wide to receive the saw blade 13 flatwise, as indicated most clearly in Figure 3 of the drawings. As

indicated in Figure 8 of the drawings, the 55 groove 12 may be deep and narrow to admit of the saw blade 13 entering the same edgewise. Reinforcing strips 14 are secured to opposite sides of the longitudinal member 10 and project a short distance beyond the 60 end member 11. Short bars 15 are slidable on the end members 11 between the projecting ends of the reinforcing strips 14. Loops 16 secured to the inner ends of the bars 15 embrace the end members 11, and retain the 65 bars 15 in position. The saw blade 13 extends between the outer ends of the bars 15 and is adapted to be strained to hold the saw either in operative position or in inoperative position, so as to be out of the way, 70 as indicated most clearly in Figure 2 of the drawings. Stems 17 loosely mounted in the outer ends of the bars 15 receive the ends of the saw blade 13 which are attached thereto in any determinate way. One of the stems 75 17 is threaded and receives a tail nut 18 whereby the stem may be adjusted longitudinally to tension the saw blade 13, or relax the tension thereon, as required when moving the saw into operative position for 80 use or adjusting it into inoperative position to be out of the way when not required for service. When the saw blade 13 is relieved of tension the bars 15 may be moved outward or inward. When the saw blade 13 85 is under tension the bars 15 are held in either extreme position substantially as indicated in Figures 1 and 2 of the drawings.

The construction illustrated admits of the frame comprising bars of wood which are 90 strengthened and reinforced by means of the strips 14 and angle irons 19 disposed in the angles formed between the members 11 and 10. Braces 20 are interposed between the members 10 and 11 and are channeled in their 95 outer sides to receive members 21 which constitute legs or branches of a compass or scribe. The legs or members 21 are pivoted at their inner ends to the braces 20 and their outer ends are pointed. Arcuate bars secured at 100 one end to the members 21 pass through openings formed in the braces 20 and are adapted to be held in an adjusted position by means of clamp screws 23 threaded into a side of the braces 20. Upon loosening the clamp screws 105 23 the members 21 may be adjusted to any required position and are held from displacement by retightening the screws 23, as will

be readily understood. A knob 24 at the outer side of each of the members 21 provides convenient means for withdrawing the members from the channel of the braces when adjusting the tool for use as a compass or scribe.

A chuck 25 is provided upon the outer side of the outer end of one of the members 11 and is adapted to receive a boring tool such as an auger 26. A knob 27 is provided at the outer end of the opposite member 11 to be grasped when the tool is adapted for use as a brace for boring when a tool, as 26, is fitted to the chuck 25. A convenient grip is provided midway the ends of the longitudinal member 10. This grip consists of an inner sleeve 27 and an outer sleeve 28. Lugs 29 project outwardly from the reinforcing strips 14 and the sleeves 27 and 28 are disposed therebetween to be maintained in a given position. The inner sleeve 27 is formed in a side with a longitudinal opening 29' to register with the groove 12, whereby provision is had for entry and exit of the saw blade 13. The outer sleeve 28 is likewise formed in a side with an opening 30 for a like purpose. The sleeves embrace the member 10, the reinforcing strips 14 and the opposing ends of the braces 20. A latch 31 is mounted upon the member 10 and is adapted to engage a notch in the adjacent end of the inner sleeve 27 to hold said sleeve stationary when the opening 29 is in register with the groove 12 so that the outer sleeve 28 may be turned to bring the opening 30 in position to register with the groove 12, whereby the saw blade 13 may enter or leave the groove 12. It will thus be understood that the sleeves 27 and 28 besides forming a grip provide retaining means for holding the saw blade 13 within the groove 12.

When the tool is adapted for boring openings the members 21 are folded within the channels of the braces 20 and the saw blade 13 is adjusted to be housed within the groove 12. An auger 26, or other boring tool, is

fitted to the chuck 25, thereby adapting the tool for use as a hand brace, as will be readily comprehended. To adapt the tool for use as a saw the boring tool 26 is removed, and the elements 27 and 28 comprising the grip 50 adjusted to bring the openings 29 and 30 in register with the groove 12 to admit of moving the bars 15 outwardly into the position indicated in Figure 1 of the drawings. When the saw blade is tensioned the bars 15 are retained in the extreme positions indicated in Figure 1 of the drawings. When the tool is desired for use as a compass or scribe the saw is adjusted so as to be out of the way and the members 21 are moved into the required position and are held in the located position by retightening the clamp screws 23 which were previously loosened to admit of adjustment of the members 21.

Having thus described the invention, I claim:

A compound tool comprising a substantially U-shaped frame, channel braces connecting the longitudinal and end members of the frame, members adapted to be housed within the channel braces and pivoted at their inner ends thereto, means for securing the pivoted members to the braces in adjusted position, reinforcing strips applied to opposite sides of the longitudinal member of the frame and 70 projecting beyond the end members to embrace the sides of bars, there being a groove in the back of the frame, bars slideable on the end bars of the frame, a saw blade connected to the ends of the sliding bars and adapted to 80 be housed within the grooved back of the frame, concentric sleeves embracing the longitudinal member of the frame and the reinforcing strips at the sides thereof and provided with openings in their sides to register 85 with the groove in the back of the frame, and means for holding the inner sleeve against rotation.

In testimony whereof I affix my signature.

FAUSTINO VISINTAINER. [L. s.]
